BATHING SUIT

Filed Aug. 8, 1927

Herbert J. Knapp, INVENTOR
BY Victor J. Evans
ATTORNEY

UNITED STATES PATENT OFFICE.

HERBERT J. KNAFF, OF AKRON, OHIO.

BATHING SUIT.

Application filed August 8, 1927. Serial No. 211,447.

My present invention has reference to a bathing suit that is particularly designed for use by ladies, and an object is the provision of an article of this class constructed of rubberized silk or cotton stockinette having a rubber facing, and also having integrally formed with the body portion of the suit a skirt whose lower edge is folded upon itself and connected to provide a tubular inflatable chamber, together with valve means of a simple but novel construction threaded to permit of the user of the suit inflating the chamber and for sustaining the said chamber inflated.

To the attainment of the foregoing and other objects which will present themselves as the nature of the invention is better understood the improvement consists in the improved construction of bathing suits hereinafter described and definitely claimed.

In the drawings:

Figure 1 is a perspective view illustrating the application of my improved bathing suit.

Figure 2 is a detail elevation to illustrate 25 the valve for the inflatable chamber.

Figure 3 is a detail sectional view through the skirt portion of the suit approximately on the line 3—3 of Figure 1.

The body portion 1 of the bathing suit is 30 integrally formed with trunks, disclosed by the dotted lines in Figure 1 and indicated by the numeral 2. The rubberized material constituting the suit at the waist thereof, is formed with a skirt extension 3 which normally covers the trunks 2. The skirt 3, at 35 its outer end is folded upon itself and the said folded portion is cemented to the inner face of the skirt. This fold provides the lower edge or bottom of the skirt with a substantially tubular inflatable chamber 4. The chamber on its outer face approximately, at the center thereof, has an opening therethrough, but passing through this opening there is a flexible, preferably rubber tube 5. The inner end of the tube 5 is flanged to provide the same with a disc-like portion 6 and this disc-like portion is cemented or otherwise effectively secured to the inner face of the outer wall provided by the chamber 4. Above the opening there is 45 secured on the outer face of the fold constituting the chamber 4 the ends of the rubber strap 7, and between this strap and the chamber the tube 5 is projected when the skirt portion 3 of the bathing suit is drawn upwardly over the trunk portion thereof so

that the tube may be received in the mouth of the user of the suit and air forced therethrough to inflate the tubular chamber 4. After the chamber is inflated the tube is 60 folded upon itself, as disclosed by Figure 3 of the drawings and arranged beneath the strap 7. The inflating chamber will stretch the strap so that the same will exert a tight pressure or frictional engagement against 65 the tube and thereby prevent the escape of air through said tube. The strap 7 is covered by a rubber rosette or other ornamental figure 8.

My improved bathing suit may be used by 70 either expert or amateur swimmers. When used by amateurs or as a matter-of-fact, when used by professionals should they find themselves exhausted, the skirt portion is folded over the body of the swimmer and 75 after the chamber 4 is inflated, as above described, the said chamber will be arranged around the chest and below the armpits of the bather. The suit is constructed of very strong but extremely light material and may 80 be folded into a neat package that may be conveniently carried when not in use.

Having described the invention, I claim:

1. A bathing suit of rubberized silk or cotton stockinette having an outer facing of 85 rubber including a body portion provided with trunks and an integrally formed skirt at the waist of the body portion that normally conceals the trunks, said skirt having its outer edge rounded upon itself and cemented to the inner face of the skirt proper to provide a tubular inflatable chamber, a tube secured to and extending from the chamber and a rubber strap having its ends secured to the outer face of the chamber 90 through which the tube is designed to be passed after the chamber has been inflated, and whereby the inflation of the said chamber will cause the stretching of the strap to permit of the latter firmly compressing 100 the tube against the chamber to prevent the passage of air through said tube.

2. A bathing suit of rubberized silk or cotton stockinette having an outer facing of 105 rubber including a body portion provided with trunks and an integrally formed skirt at the waist of the body portion that normally conceals the trunks, said skirt having its outer edge rounded upon itself and cemented to the inner face of the skirt proper to provide a tubular inflatable chamber, and the outer wall of the chamber having a cen-

tral opening therethrough, a flexible tube received through the opening and having an inner outwardly extending flanged portion which is cemented to the inner wall of the outer face of the chamber, an elastic strap having its ends secured to the outer face of the chamber above the opening through which the tube passes and designed to be expanded by the chamber when the latter is

inflated and being also designed to receive 10 the tube therethrough when the latter is folded to compress the said tube against the chamber to prevent passage of air through said tube, and an ornamental figure passing through the said strap. 15

In testimony whereof I affix my signature.

HERBERT J. KNAPP.
